UNITED STATES PATENT OFFICE.

WILLIAM GEORGE MEDDINGS, OF REMUERA, NEAR AUCKLAND, NEW ZEALAND.

AUTOMATIC ELECTRIC FIRE-ALARM.

No. 841,557.

Specification of Letters Patent.

Patented Jan. 15, 1907.

Application filed March 6, 1906. Serial No. 304,569.

To all whom it may concern:

Be it known that I, WILLIAM GEORGE MEDDINGS, inspector of New Zealand telegraphs, a subject of His Majesty the King of the 5 United Kingdom of Great Britain and Ireland, and a resident of Remuera, near the city of Auckland, in the Provincial District of Auckland and Colony of New Zealand, have invented an Automatic Electric Fire-Alarm, 10 of which the following is a specification.

The purpose of this electric fire-alarm is to give the alarm wherever the apparatus is fixed on the temperature of the room, chamber, or compartment rising to 150° Fahrenheit and upward. This is accomplished by a 15 disk or piece of metal held by claws softening by the increase of heat, so releasing the tension of the rod pressing thereon, and thereby permitting the spring pressed up by the rod 20 to engage the fixed connection whereby contact is made, an electric circuit established, and the alarm given by means of any suitable apparatus fitted thereto.

The accompanying drawings, which are 25 full size, show three figures, of which—

Figure 1 is an elevation of the electric alarm device, showing portion of its upper part broken. Fig. 2 is a sectional view of the device, and Fig. 3 is a perspective view 30 of the disk or piece of metal fitted to the claw-legs.

The disk or piece of metal A is made of a composition, preferably of a mixture of bismuth, tin, and lead, which softens in an atmosphere of a temperature of 150° Fahrenheit and upward and is held in a claw formation B, made by three pieces of brass wire C, which are screwed or otherwise fixed or attached to one end D of a small brass tube E. 35 A small brass rod F is passed up the center of the tube E, the lower end G of which is placed and pressed against the middle of the disk or plate A. The rod F is held in position by a spiral spring H, one end of which presses 40 against the bottom of the case K, the other end against the nut X, which is fixed to the rod F, thus causing a continuous pressure on the center of the piece of metal A. The upper end J of the rod F passes upwardly out 45 of the tube E into a small case K, attached to the tube E. Two electric contacts M and N, made of thin metal, are adjusted inside the case K, as shown in Fig. 2, M being a movable spring, and N a fixture. The end

J of the rod F raises the spring M up and 55 keeps a space between it and the metal N, while the disk or piece A retains its normal condition. When, however, the temperature is raised to 150° Fahrenheit or over, the pressure exerted on the spiral spring H on 60 the rod overcomes the resistance of the disk or piece A, which has softened by the increased heat, so that it bulges and breaks and allows the spring M to form contact with the fixed piece N, thereby establishing an 65 electric circuit and giving an alarm by means of the apparatus and batteries connected to the wires P and R. Vulcanite S or any insulating material is fitted in cap O and in the top part of the upper case T to prevent the 70 wire being in any way brought into accidental contact with the case. Bayonet-joints U are provided in the upper and lower cases to provide for their being held together, as required, and screws to hold the vulcanite and 75 insulated wires in position. The nut W is fastened to the under part of the lower case K and is inwardly screw-threaded, so that the top of the tube E, which is outwardly screw-threaded, can be screwed into it and 80 so be attached to the case K or may be bayonet-jointed, as desired.

The outer parts of the apparatus, except the disk or piece of metal A, are coated with aluminium paint, so as to protect it from foul 85 air, moisture, and other corroding agencies. This apparatus may be fitted in buildings and ships of all descriptions and any number of contacts (apparatus described above) fitted in parallel right throughout or divided 90 into sections, as may be desired. The number of contacts fixed in each room, chamber, compartment, or hold of vessel would be in proportion to the area of same.

Having fully described my invention, what 95 I desire to claim and secure by Letters Patent is—

1. The combination in the automatic electric fire-alarm specified of the disk or piece of metal made of a mixture of bismuth tin and 100 lead which will soften in a temperature of 150° Fahrenheit held in claw formation of three pieces of brass wire fixed to one end of small brass tube, small brass rod passed up center of said tube with lower end of said rod 105 placed to press against middle of said disk or piece of metal, spiral spring around said rod held between nut fixed to said rod and lower

case, upper end of said rod passing upwardly out of said tube into said lower case, electric contacts adjusted inside of said case one being a fixture and the other movable, upper end of said rod fitted to actuate said movable contact, insulated wires connected to said contacts upper case and bayonet-joints fitted therein and in lower case, cap on top of upper case, vulcanite fitted in said cap and top of upper case, nut fastened to under part of said lower case and upper end of said tube-screw fitted to said nut for the purpose set forth substantially as described and illustrated.

2. The combination in the automatic electric fire-alarm specified of the disk or piece of metal made of a mixture of bismuth tin and lead which will soften in a temperature of 150° Fahrenheit held in claw formation of three pieces of brass wire fixed to one end of small brass tube, small brass rod passed up center of said tube with lower end of said rod

placed to press against middle of said disk or piece of metal, spiral spring around said rod held between nut fixed to said rod and lower case, upper end of said rod passing upwardly out of said tube into said lower case, electric contacts adjusted inside of said case one being a fixture and the other movable, upper end of said rod fitted to actuate said movable contact, insulated wires connected to said contacts and to source of electrical energy an upper and lower case provided with bayonet-joints, cap on top of upper case, vulcanite fitted in said cap and top of upper case, nut fastened to under part of said lower case and upper end of said tube-screw fitted to said nut for the purpose set forth substantially as described and illustrated.
